DESIGN FOR A VEGETABLE AND STORAGE
CABINET

Robert W. Conner, East Brookfield, Mass.

Application March 18, 1946, Serial No. 127,615

Term of patent 7 years

(Cl. D33—19)

To all whom it may concern:

Be it known that I, Robert W. Conner, a citizen of the United States, residing at East Brookfield, in the county of Worcester and State of Massachusetts, have invented a new, original, and ornamental Design for Vegetable and Storage Cabinet, of which the following is a specification, reference being had to the accompanying drawing, forming part thereof.

Fig. 1 is a front elevational view of a vegetable and storage cabinet, showing my new design;

Fig. 2 is a side elevational view, taken from the right in Fig. 1;

Fig. 3 is a top plan view, and

Fig. 4 is a sectional side elevation, taken along the line 4—4 in Fig. 1.

I claim:

The ornamental design for a vegetable and storage cabinet, as shown.

ROBERT W. CONNER.
